ABSTRACT: A two-piece multiposition ripper attachment for a back hoe is disclosed. In a first position, the attachment is stored out of the way so as to not interfere with normal use of the back hoe. In a second position, the attachment and method is exposed so that the back hoe may be used as a ripper in one orientation and may be used to perform its normal functions in a second orientation.

METHOD AND APPARATUS FOR USING A BACK HOE BUCKET AS A FROZEN GROUND RIPPER

This invention relates to attachments for movable buckets and more specifically to a ripper attachment for a back hoe bucket. The prior procedures for breaking up frozen ground, asphalt or other similar surfaces has been to use a large cable-operated machine and merely drop the bucket so as to break through the hard surface. This is obviously hard on the machine. There are also special purpose machines designed for this ripping process. Small machines equipped with a back hoe bucket are generally incapable of coping with this problem.

Accordingly, it is one object of the present invention to provide an attachment for a back hoe bucket which attachment may be used to rip or tear through a crustaceous surface such as frozen ground or asphalt.

It is another object of the present invention to provide a ripping attachment which does not interfere with the normal use of the back hoe bucket.

The present invention contemplates a two-piece ripper attachment for a back hoe bucket. When the attachment is in one position, the back hoe may be used to perform its normal scooping operations in one orientation and may be used as a ripper in a second orientation. When the attachment is in another position it is stored out of the way so as to not interfere with any of the normal uses of the back hoe bucket.

Accordingly, it is another object of the present invention to provide a retractable ripper attachment for a bucket.

When the attachment is in its ripping orientation the bucket serves as a guide so as to not allow the ripper to dig too deeply and thus become hung up or stuck.

It is a further object of the present invention to provide a ripper attachment which is economical to manufacture and easy to install.

These and other objects and advantages of the present invention will become more readily apparent from the subsequent disclosure read in conjunction with the accompanying drawing in which like parts are indicated by like numerals:

FIG. 1 shows the ripper attachment in its retracted position on a back hoe bucket;

FIG. 2 shows the ripper attachment in its operating position on a back hoe bucket;

FIG. 3 is an end view taken along the line 3-3 of FIG. 1; and FIG. 4 is a sectional view taken along the line 4-4 of FIG. 2.

Referring now to FIG. 1, a bucket or scoop 1 is shown with the ripper attachment in place. The front end 2 of the bucket is used to scoop material. The rear end of the bucket has a rearwardly projecting portion 4 provided with one or more holes 5. These holes are normally provided on the bucket to allow variations in the point of attachment of the two levers 3 and 6 for specialized digging operations. Thus, the particular back hoe bucket illustrated in FIG. 1 might occasionally be used with the lever 6 attached by means of a pin through the hole 5 rather than through the hole 7. As a general rule this hole 5 is not used for lever attachment and is thus available to attach the novel ripper of the present invention. Of course, the orientation of the bucket 1 is controlled during use by the relative orientation of the levers 3 and 6. These levers may be hydraulically operated.

As shown in FIG. 1 applicant's attachment is seen to consist of a bracket portion 8 provided with a plurality of apertures or holes at the points 5, 9 and 10. The aperture at 5 allows the bracket to be attached by means of a pin through the corresponding holes in the rearwardly projecting portion of the bucket. The attachment further consists of a scarifier portion 11 shown as a vertically extending shank and a bit or tooth 12 attached to the lower end of the shank. In a preferred embodiment, this shank is of rectangular cross section and is provided with at least one hole so that the shank may be attached to the bracket portion by means of a pin generally indicated at 9 in FIG. 1. Either the bracket or the shank or both are provided

with a plurality of holes so that the pin at 9 may be removed and the shank portion lowered to its operational position as is shown in FIG. 2. In the particular embodiment illustrated in FIGS. 1 and 2, the shank portion has one or any number of holes and the bracket portion has one or any number of holes to allow for this adjustment.

The specific structure of a preferred embodiment of the present invention is most readily seen in reference to FIG. 3 which shows a bucket 1 having a bracket portion 8 attached to the rearwardly projecting portion of the bucket by means of a pin 13 which pin is held securely in place by the retaining ring 14. This pin is seen in FIG. 1 as extending through the hole at 5 which hole passes through both the bracket and the rearwardly projecting portion of the bucket. The shank portion 11 of the scarifier is attached to the bracket portion 8 by means of a removable pin 15 which passes through aligned holes in the bracket and the shank portion. This pin is held in place by a retainer 16.

Turning now to FIG. 4 the rearwardly projecting portion of the bucket is seen to consist of two parallel pieces 17 and 18 and the pin 13 is seen to pass through a hole in 17, a hole in the bracket portion 8, and then a hole in 18 and to be held in position by the retaining ring 14. The shank 11 of the scarifier portion is seen to be attached to the bracket portion by the removable pin 15 which passes simultaneously through a first side of the bracket 19 through the shank 11 and subsequently through the other side of the bracket at 20. This pin 15 is held in position by an easily removable retainer 16. The shank is further held in position by a backing plate 21 on the bracket 8. For additional strength, gussets or braces 22 may be welded to the sides 19 and 20 so as to more securely hold them to the body of the bracket 8.

In light of the above structural disclosure, the installation and operation of the attachment may now be easily followed. The present device would typically be used as an attachment to the back hoe bucket of a tractorlike vehicle. Such buckets typically have several holes which serve as points of attachment for the mechanical linkage which operates the bucket. There are normally more holes than necessary for operating the bucket. The present attachment is fastened by a casehardened pin to one of these extra holes such as illustrated at 5 in FIG. 1. The scarifier portion of the attachment is then slidably mounted within the bracket portion 8 by means of a second pin. The bracket and scarifier are provided with several holes so that this second pin may be inserted so as to hold the entire attachment out of the way during extended periods of normal bucket use or may be held in a lower position for use of the attachment.

The advantages of this device should now also be clear. The device is easy to install and no special tools or modifications of the bucket are necessary. The device need not be removed in the summertime but can be left on the bucket in its up or stored position. The device cannot hang up by going too deep. By this, I mean, the bucket serves as a guide or depth gauge, thus the bucket of FIG. 2 will disrupt or loosen frozen ground to a depth limited by the bottom of the bucket contacting the surface of the ground. If the bucket of FIG. 2 is rotated slightly clockwise, it will tear at a lesser depth. As the bucket is rotated counterclockwise, it will dig at a deeper and deeper depth until it reaches a point where the tooth or bit 12 is angled relative to the earth in such a way as to force the entire attachment back out of the ground. Thus, the attachment kicks itself out when digging too deeply. The angle of inclination of the tooth 12 relative to the shank 11 may of course be varied from that shown in the drawing.

Several other modifications will immediately suggest themselves to those skilled in this art, thus, the tooth or bit on the end of the scarifier may be made to be replaceable on the end of the shank portion so that the entire shank and bit need not be replaced when the bit is worn out. Similarly, this tooth may be made pointed, that is, to have a triangular horizontal cross section rather than rectangular as shown in FIG. 3. These and other modifications will readily suggest themselves to those of

ordinary skill in the art and accordingly the invention is to be limited only by the scope of the following claims.

I claim:

1. An attachment for use in conjunction with a movable bucket or the like, the front end of said bucket being adapted to be used to scoop material, the rear end of said bucket having at least one rearwardly projecting portion provided with at least one transverse aperture, said rear end of said bucket adapted to receive said attachment, said attachment comprising:
  - a bracket portion provided with a plurality of apertures, a first of said apertures being adapted to removably attach said bracket portion to said rearwardly projecting portion;
  - a scarifier portion comprising a shank and a bit, said shank being elongated, said bit attached to said shank in the proximity of one end of said shank, said shank being provided with at least one aperture;
  - a pin adapted to pass simultaneously through another of said apertures in said bracket portion and an aperture in said shank portion to hold said scarifier portion in a first position with respect to said bracket portion, said pin being adapted to be removed and reinserted to align a second pair of apertures so as to hold said scarifier portion and said bracket portion in a second relative position.
2. The attachment of claim 1 wherein the bracket portion comprises a pair of separated parallel side portions and an attaching portion, said side portions adapted to confine said shank therebetween, said shank being of substantially rectangular cross section.
3. The attachment of claim 2 wherein said attaching portion is adapted to be attached to said rearwardly projecting portion of said bucket by a transversely disposed pin.

4. The attachment of claim 2 wherein one of said shank and said pair of parallel side portions is provided with one aperture and the other is provided with two apertures so disposed that a first combination of said apertures may be pinably aligned to hold the scarifier portion in said first position and that a second combination of said apertures may be pinably aligned to hold the scarifier portion in said second position.
5. The method of using a back hoe to break up and move a horizontally disposed crustaceous material comprising the steps of:
  - attaching to the back hoe bucket in a first position a scarifier;
  - revolving the bucket to a first orientation wherein the scarifier is exposed below the lower edge of the bucket;
  - moving the bucket and attached scarifier horizontally so as to rip the material;
  - revolving the bucket to a second orientation so that the scarifier is obscured behind the bucket;
  - scooping up the thus loosened material into the bucket for removal and;
  - moving the scarifier attachment to a second position for storage during periods of nonuse.
6. The method of claim 5 wherein the step of moving comprises making a plurality of substantially parallel ripping passes.
7. The method of claim 6 wherein said plurality is three.
8. The method of claim 5 wherein the step of moving the scarifier to its second position comprises the steps of sliding the scarifier attachment upwardly with respect to the bucket, and affixing it to the bucket in said second position so as to effectively store the scarifier in said second position during periods of nonuse.
